MEANS FOR FEEDING METAL TO THE
METAL POTS OF TYPOGRAPHICAL CAST-
ING MACHINESChristian Augustus Albrecht, Berlin, Germany,
assignor to Mergenthaler Linotype Company,
Brooklyn, N. Y., a company of New YorkApplication June 9, 1934, Serial No. 729,729

6 Claims. (Cl. 22—80)

This invention relates to apparatus for feeding metal ingots to the metal pots of typographical casting machines, of the kind in which the ingot is provided with teeth and is supported above the metal pot in a substantially vertical guide, with its teeth in engagement with a rotary member which is locked against its tendency to rotate under the weight of the ingot, by a stop or abutment adapted to be released through the movement of the metal pot. It sometimes happens that a metal ingot, by reason for example of the presence thereon of burrs or other irregularities, sticks in its guideway. This makes it necessary for the rotary member engaged by the teeth of the ingot to be reversed to permit the ingot to be lifted out. Such reverse movement cannot be effected conveniently, and it is the object of the present invention to facilitate the removal of the ingot under the conditions stated.

According to the invention, the rotary member is mounted in open bearings, preferably in inclined slots, so that the said member can be raised upwardly out of its bearers with the metal ingot. The invention further includes provision for the convenient removal of the apparatus as a whole, when it is desired to use ingots without teeth or old slugs, and to facilitate cleaning.

The accompanying drawing illustrates by way of example, one constructional form of the invention, and in the drawing:—

Figure 1 is a side elevation of the feeding apparatus;

Figure 2 is a plan thereof, and

Figure 3 is a plan view of the control bar removed from the apparatus.

In the drawing, 1 is the metal pot cover, upon which is mounted the guide 2 for the metal ingot 3. The metal ingot is provided with teeth 4 adapted to engage with a toothed wheel 5. Upon the spindle 6 of the wheel 5 is mounted a disc 7 carrying laterally extending pins 8 arranged substantially circumferentially around the face of the disc. These pins 8 are adapted in turn to rest upon the upper edge of a longitudinally movable bar 9 provided with an inclined slot 10, the upper end of which is brought beneath the pin 8 resting upon the bar for the time being, when the bar is moved longitudinally as hereinafter described.

50 A lever 11 is pivotally mounted upon a stud 12 fixed to the bar 9. This lever 11 has a fork 13 at one end, which supports a pin 14 passing through a float rod 15 carrying a float 16 suspended inside the metal pot. At the opposite end of the lever 11, there is a projection 17 which

is brought into engagement with a fixed, preferably adjustable, stop 18 when the metal pot is moved forward to the casting position.

By this arrangement, when the float 16 is at a level at which it is necessary to feed more metal to the pot, the lever 11 is in such a position that when the metal pot moves forward, i. e., towards the right as viewed in Figure 1, the projection 17 strikes against the stop 18 and causes the bar 9 to be displaced to the left relatively to the spindle 6. The slot 10 is thus brought beneath the particular pin, for example 8^a, which had just previously been supported on the upper edge of the bar 9 and the said pin passes into the slot 10 under the influence of the weight of the metal ingot. When the projection 17 is carried away from the stop 18 on the return movement of the metal pot, the pin passes through the slot 10, the inclination of which is such that the pin 8^a, during its passage therethrough in an arctual path, moves the bar rightwardly to its normal position. The upper end of the slot is thus brought out of the path of movement of the next succeeding pin 8, which comes into engagement with the upper edge of the bar and arrests the rotation of the disc 7 and wheel 5. The ingot 3 is thus fed downwardly to an extent equal to the pitch of its teeth, and the parts again set for repeating the feed operation at the next succeeding movement of the metal pot should the float still be low enough to hold the projection 17 in a position to engage the stop 18.

The bearings 19 of the spindle 6 are formed with inclined slots 20 open at the top so as to permit the spindle to be lifted out upwardly without necessitating the removal of a bearing cap or cover. Further, the bearings 21 for the bar 9 are also open at the top, so as to permit of the free removal of the said bar. Moreover, the float 16 is also removable upwardly by reason of its loose suspension in the fork 13 by the pin 14. By the aforesaid arrangement of the bearings, it is possible to lift the ingot 3 upwardly when it becomes fast in its guideway, the spindle 6, together with the wheel 5 and disc 7 mounted on it being lifted upwardly out of the bearings 19. Through the inclined arrangement of the slots 20, the spindle, during the normal operation, is securely held in its place, as the teeth 4 on the ingot 3 acting upon the wheel tend to force the spindle downwardly upon the inclined bearing surfaces. After the spindle 6 has been removed, the bar 9 with the lever 11 fast thereon, can also be lifted conveniently, provided the float has previ-

ously been unhooked from the fork 13 of the lever 11.

The inclination of the slots 20 for the bearings of the spindle 6 must be so selected that, while the weight of the ingot 3 will be adequate to securely hold the spindle in its operative position, the convenient raising of the spindle is permitted when the ingot is moved upwardly, by the engagement of the teeth 4 with the pins 8.

10 The bearings 19 for the spindle 6 as well as the bearings 21 for the bar 9 are made in one piece with the guide 2 and a plate 22, which can be conveniently connected to the metal pot cover by screws or the like.

15 Having described my invention, I declare that what I claim and desire to secure by Letters Patent is:—

1. In a typographical casting machine, mechanism for feeding metal ingots provided with teeth to a metal pot movable to and from casting position comprising in combination a substantially vertical guide for the ingot, a rotary member adapted to be engaged by the teeth on the ingot, an abutment normally locking said member against its tendency to rotate under the weight of the ingot and adapted to be withdrawn from and returned to the locking position through movement of the metal pot, and open bearings for the rotary member permitting said member to be removed with the ingot when the latter is withdrawn upwardly from the guide.

2. In a typographical casting machine, mechanism for feeding metal ingots provided with teeth to a metal pot movable to and from casting position comprising in combination a substantially vertical guide for the ingot, a rotary member adapted to be engaged by the teeth on the ingot, a longitudinally movable bar normally locking said member against its tendency to rotate under the weight of the ingot and adapted to be withdrawn from and returned to the locking position through movement of the metal pot, and open bearings for the rotary member and longitudinally movable bar permitting said member and bar to be removed with the ingot when the latter is withdrawn upwardly from the guide.

3. Mechanism according to claim 2, characterized by a common base plate carrying the ingot guide, the bearings for the rotary member and the bearings for the longitudinally movable bar, whereby the mechanism may be secured to and detached from the metal pot as a single entity.

4. In a typographical casting machine, mechanism for feeding metal ingots provided with teeth to a metal pot movable to and from casting

position comprising in combination a substantially vertical guide for the ingot, a rotary member adapted to be engaged by the teeth on the ingot, a longitudinally movable bar normally locking said member against its tendency to rotate under the weight of the ingot and actuated to release and relock said member through the movement of the metal pot, a float detachably connected to the bar controlling the actuation thereof, and open bearings for the rotary member and longitudinally movable bar permitting said member and bar to be removed with the ingot when the latter is withdrawn upwardly from the guide.

5. In a typographical casting machine, mechanism for feeding metal ingots provided with teeth to a metal pot movable to and from casting position comprising in combination a substantially vertical guide for the ingot, a rotary member adapted to be engaged by the teeth on the ingot, a longitudinally movable bar normally locking said member against its tendency to rotate under the weight of the ingot, open bearings supporting said bar, a lever pivoted to said bar, a float rod detachably suspended from one end of said lever, a fixed abutment adapted to be engaged by the opposite end of said lever to move the bar in one direction relatively to the rotary member as the metal pot moves to casting position, means adapted to move the bar in the opposite direction during the movement of the metal pot from casting position, and open bearings for the rotary member permitting it to be removed with the ingot when the latter is withdrawn upwardly from the guide.

6. In a typographical casting machine, mechanism for feeding metal ingots provided with teeth to a metal pot movable to and from casting position comprising in combination a substantially vertical guide for the ingot, a rotary member adapted to be engaged by the teeth on the ingot, lateral projections operatively fast to the rotary member, a longitudinally movable bar having an inclined slot and adapted to lock and release the rotary member by movement of its slotted portion out of and into register with said projections successively, the passage of a projection through the inclined slot serving to restore the bar to locking position, means actuated by the movement of the metal pot to move said bar to the unlocking position and open bearings for the rotary member and longitudinally movable bar permitting said member and bar to be removed with the ingot when the latter is withdrawn upwardly from the guide.

CHRISTIAN AUGUSTUS ALBRECHT.
